MEANS FOR IMPREGNATING FELT OR OTHER FABRICS

Application filed January 27, 1927. Serial No. 164,019.

In the manufacture of felt base floor covering, roofings and similar articles where it is necessary to impregnate rag felts and other fabrics to the point of saturation with heated asphaltum, or other saturating agents, there is considerable waste due to the breaking of the web in the saturating tanks. The wider the web, the more waste there is. Deep tanks equipped with bates are necessary to saturate the web, as well as cooling drums, drying loopers, etc., not to mention the employment of skilled labor to attend the different phases of the operation.

In the roofing industry two kinds of asphalts are being used; one for saturating, the other for coating purposes. The first kind referred to is chiefly a soft, steam-refined product selected for its capacity to penetrate the web and a product susceptible to changes of temperature. The second, oxidized rubbery asphalt, is much less susceptible to changes of temperature and used as a coating medium into which slate granules are pressed, while the asphalt is hot.

In the felt-base floor-covering industry, a fairly hard, steam-refined asphalt of a higher melting point as compared with roofing saturating asphalt, is being used, which is even more susceptible to temperature changes than roofing asphalt.

My invention relates to an improved apparatus for the saturating phase of treating the materials referred to for effecting thorough and complete saturation. The invention is useful for the purpose of impregnating floor covering, roofing and other felts or fabrics with a suitable oxidized, rubbery asphaltum or other saturants, the general object being to produce saturated felts that will be elastic, strong, taut and water-proof.

Reference is to be had to the accompanying drawings forming part of this specification which represent one means for carrying out the invention.

Figure 1 is a longitudinal, vertical section

of an apparatus for carrying out my invention, the section being taken on the line 1—1 of Figure 2;

Figure 2 is a plan view with parts in section on the line 2—2 of Figure 1;

Figure 3 is a transverse vertical section on the line 3—3 of Figure 1;

Figure 4 is a detailed end view of the drawing rollers.

In carrying out my invention in accordance with the illustrated example a tank 10 adapted to hold asphaltum or other impregnating or saturating material is provided. A supply pipe 11 adapted to be connected to any convenient source of supply of asphaltum or the like is disposed above tank 10 and has a distributing head 12 formed with a plurality of outlets 13 for the asphaltum. The outlets 13 discharge to nozzles 14 (Figures 1 and 2) terminating in pouring spouts 15. The fabric A is passed through feed rollers 16 and downward beneath an idler roller 17 adapted to have the material poured thereon by the spouts 15. From idler roller 17 the fabric A passes over a suction cylinder 18 in which a dry vacuum is maintained, as will appear, then downward over an idler roller 19 submerged in the tank 10 and through squeezing rollers 20. Cylinder 18 is perforated at the top.

An air pipe 21 communicates suitably with the interior of the suction cylinder 18, as through opening 22 which also constitutes a drain hole for the asphaltum drawn into the cylinder 18, so that the asphaltum collecting in said cylinder 18 will finally pass to a drain pipe 23 which may be disposed above any suitable catch basin or lead to any convenient source.

The idler rollers 17 and 19 tension the fabric A sufficiently, for which purpose said rollers are mounted respectively in frames 24, 25, the journals of the idlers 17, 19 having clearance in vertical slots 26, 27 provided by guides 28, 29 on tank 10. The lower one of

squeezing rollers 20 is journaled in vertical frame 30 supported on tank 10 or otherwise, while journals of the upper roller 20 turn in bearings 31, vertically adjustable in guide slots 32, in response to the operation of adjusting screws 33.

Frame 24 has a rack 50 engaged by pinion 51 on handled shaft 52. Frame 25 has a rack 53 engaged by pinion 54 on a handled shaft 55. Thus both frames 24 and 25 may be raised or lowered.

In order to adapt the apparatus for effectively impregnating fabrics of different widths without waste and with economy, I provide means for varying the effective suction area of the cylinder 18, for which purpose use is made of arcuate shields 34 on segmental webs 35 having hubs 36 engaging right and left threads on adjusting shaft 37, having radial ends 38, whereby to cover by said shields 34 more or less of the perforated top of cylinder 18.

With the described construction suction produced in pipe 21 will cause a vacuum within the cylinder 18 and it is to be observed that said cylinder 18 is above the level of the asphaltum in tank 10, whereby a dry vacuum is maintained. So much of cylinder 18 as is exposed between radial guards 38, will be subject to the suction, and as the pouring spouts 15 are in advance of the cylinder 18 the fabric A will pass over said cylinder after the pouring of the asphaltum on to the roller 17 and therefore on to the fabric A. The fabric thus coated with asphaltum will be subjected to suction and the asphaltum will be drawn into the fabric in passing over the top of cylinder 18 and effective saturation of the fabric will result. As the fabric moves downward into the asphaltum in the tank 10 and about roller 19 it will be again thoroughly coated on both sides with the asphaltum and the surplus asphaltum will finally be removed by reason of the squeezing rollers 20. It is to be understood that the cylinder 18 is turned continuously, there being shown for the purpose a drive shaft 39 on the end of adjusting shaft 37 and driven in any suitable manner, as by a pulley 139. The cylinder 18 at one end is turnable with the shaft 39 as seen at the right of Figure 3 while at the opposite end said cylinder 18 is turnably mounted on a hollow bearing 41 supported on tank 10, said hollow bearing 41 forming a passage for the asphaltum to drain from the cylinder 18 to drain opening 22. The extension 42 on bearing 41 has a bearing 43 for one end of adjusting shaft 37, the opposite end of said adjusting shaft having a bearing as at 44 in the end of hollow bearing 41.

The positioning of cylinder 18 above the liquid level in the tank 10 insures a dry vacuum for effectiveness in drawing the asphaltum into and through the felt or fabric, and at the same time prevents filling of the vacuum

cylinder by the asphaltum, which would minimize the vacuum. The confining of the suction area to a limited sector of the cylinder also concentrates the action in increasing the efficiency of the apparatus.

In order that the impregnating of the felt or other fabric through the medium of the suction through cylinder 18 may be the more effective I provide for drawing the air from the interstices and bores of the fabric preparatory to the application of the asphaltum for impregnating the material. For the stated purpose I extend the perforated area at the top of the cylinder 18 to sufficient extent so that the suction is effective between the roller 17 and the nozzle 15. Thus air will be drawn from the fabric directly before the fabric reaches the asphaltum, it being understood that the suction of the fabric preliminary to the application of the asphaltum may be otherwise produced.

I would state furthermore that while the illustrated example constitutes a practical embodiment of my invention, I do not limit myself strictly to the exact details herein illustrated, since, manifestly, the same can be considerably varied without departure from the spirit of the invention, as defined in the appended claims.

What I claim is:

1. In an apparatus for impregnating felt and other fabrics, a tank to hold the impregnating material, means above the level of the material in the tank to guide fabric through the apparatus, means above said level to direct impregnating material on to the fabric, means to produce a suction at the opposite side of the felt from that on to which the impregnating material is directed, and means to cause the fabric to dip into the material in the tank after the application of the suction to the fabric.

2. In an apparatus for impregnating felt or other fabrics, a tank to hold impregnating material, a revolving suction cylinder above the level of the liquid in the tank to be out of contact with said liquid, means to pass the fabric to be impregnated over the top of and in contact with the suction cylinder, and means adjacent the suction cylinder to direct impregnating material on to the fabric while passing over and in contact with the cylinder, and means for directing the fabric from the cylinder to the tank.

3. In an apparatus for impregnating felt or other fabrics, a tank to hold impregnating material, a revolving suction cylinder above the level of the liquid in the tank, means to pass the fabric to be impregnated over and in contact with the suction cylinder, and means adjacent the suction cylinder to direct impregnating material to the fabric while passing over and in contact with the cylinder, together with adjustable means to vary the effective suction area of said cylinder, and

means for directing the fabric from the cylinder to the tank.

4. In an apparatus for impregnating felt and other fabrics, means to feed fabric through the apparatus, a tank to hold the impregnating material, means to direct the fabric into the tank when being fed through the apparatus, means for applying impregnating material to the fabric, and suction means over which the fabric is passed after the application of impregnating material, said suction means being above the liquid level in the tank so that the suction acts on the impregnated fabric before being directed to the tank.

KARL H. SCHUTTE.
